DESIGN FOR A TEMPERATURE INDICATOR OR SIMILAR ARTICLE

Reynold T. Hedfield and Hans Seegers, Chicago,
Ill., assignors to Jas. P. Marsh Corporation,
Chicago, Ill., a corporation of Illinois

Application August 30, 1937, Serial No. 71,390

Term of patent 14 years

To all whom it may concern:

Be it known that we, Reynold T. Hedfield and Hans Seegers, citizens of the United States, residing at Chicago, in the county of Cook and State of Illinois, have invented a new, original, and ornamental Design for a Temperature Indicator or Similar Article, of which the following is a specification, reference being had to the accompanying drawing, forming a part thereof.

The figure is a perspective view of the tem-

perature indicator or similar article showing our new design.

The dominant features of our new design reside in the casing as shown.

We claim:

The ornamental design for a temperature indicator or similar article substantially as shown, and described.

REYNOLD T. HEDFIELD.
HANS SEEVERS.
